Attn:

UNITED STATES PATENT OFFICE.

CHARLES SCHREBLER, OF LAWRENCE, MASSACHUSETTS.

DESIGN FOR A LINK FOR SPROCKET-CHAINS.

SPECIFICATION forming part of Design No. 24,799, dated October 29, 1895.

Application filed August 27, 1895. Serial No. 560,704. Term of patent 14 years.

To all whom it may concern:

Be it known that I, CHARLES SCHREBLER, of Lawrence, in the county of Essex and State of Massachusetts, have invented and produced a certain new and original Design for Links for Sprocket-Chains, of which the following is a specification.

This invention relates to a new and original design for links for sprocket-chains; and it consists in a new and original shape and configuration of the link, as hereinafter fully described and claimed, and clearly illustrated in the drawing.

In the drawing is represented a perspective view showing my design, and it is thought to be all that is necessary to fully illustrate the same.

The leading feature of my design consists in a link having a rectangular portion formed with lugs upon two of its opposite sides, and of the other two sides of said link one is of a general circular shape or contour, while the other is hooked-shaped, as shown.

a represents the rectangular portion of the link. *a'* *a²* represent the lugs formed upon the opposite sides of *a³* *a⁴*, as shown. *a⁵* represents one of the other sides of said link that is of general circular contour. *a⁶* represents the hook formed upon the fourth side *a⁷* of said link. The hook and the lugs *a'* *a²* are all in the same general plane as the rectangular portion of the link.

What I claim is—

The design for a link for sprocket chains, as herein shown and described. 35

In testimony whereof I have signed my name to this specification, in the presence of two subscribing witnesses, this 24th day of August, A. D. 1895.

CHARLES SCHREBLER.
